specification for Design.

Patented July 21, 1914.

Application filed June 13, 1914. Serial No. 845,030. Term of patent 3½ years.

To all whom it may concern:

Be it known that I, PAUL MOHRMANN, a citizen of the United States, residing at Chicago, in the county of Cook and State of Illinois, have invented a new, original, and ornamental Design for Plates for Lighting-Fixtures, of which the following is a specification, reference being had to the accompanying drawings, forming a part thereof.

In the drawings:—Figure 1 is a bottom plan view of a plate embodying this design. Fig. 2 is a section taken as indicated at line 2—2 on Fig. 1.

I claim:—

The ornamental design for a plate for lighting fixtures.

In testimony whereof I have hereunto set my hand at Chicago, Illinois, this 1st day of June, 1914.

PAUL MOHRMANN.
